FABRIC OR CLOTH UNWINDING OR UNROLLING MACHINE

Filed Aug. 23, 1923

Patented Feb. 19, 1929.

1,702,971

UNITED STATES PATENT OFFICE.

WOOTTON WALTON JEFFRESS, OF DALLAS, TEXAS.

FABRIC OR CLOTH UNWINDING OR UNROLLING MACHINE.

Application filed August 23, 1923. Serial No. 659,017.

My invention relates to improvements in 55
unwinding or unrolling machines for fabric,
paper, etc., and it consists in the combinations,
constructions and arrangements herein de-
scribed and claimed.

An object of the invention is to provide a
device of the character described which af-
fords facilities for supporting a bolt or roll
of fabric so that the fabric may be wound on
10 or unwound from the bolt or roll to permit
of desired lengths of the fabric being taken
therefrom or placed thereon in an expeditious
manner and without there being any necessity
of the lengths of the fabric being folded by
15 hand.

A further object of the invention is to pro-
vide a machine of the character described
which provides means whereby large quan-
tities of fabric or like material may be wound
20 or rolled into bolts or rolls or unwound or
unrolled therefrom in a relatively short time
and without injury to the goods or causing
soiling thereof.

A further object of the invention is to pro-
25 vide in a machine of the character described
means adjustable to rotatably support bolts
or rolls of various lengths within a consider-
able range of sizes.

Other objects and advantages will be ap-
30 parent from the following description, con-
sidered in conjunction with the accompanying
drawings, in which

Figure 1 is a top plan view of a machine
35 embodying the invention, portions thereof
being broken away and other portions being
shown in section.

Figure 2 is a side elevation of the machine,
and

Figure 3 is an end view of the same.

40 In carrying out my invention in the form
now preferred by me, I provide a frame desig-
nated generally at 1 which includes an elon-
gated hollow frame section 2 which is shown
as comprising a pair of spaced apart par-
45 allel side members 3 having the upper end
portions thereof bent inwardly or toward
each other to lie in a horizontal plane as
indicated at 3^a and having at their lower ends
outwardly extending flanges 3^b each provided
50 with a series of bolt receiving openings 4 ex-
tending longitudinally thereof. The sides 3
of the frame section 2 are rigidly secured
together at one end of the frame by a trans-
verse plate 5. The frame section 2 is closed

along its lower side by a bottom plate 6 which
has series of openings 7 respectively in regis-
ter with the corresponding openings 4 of the
series of openings in the flanges 3^b and bolts
8 may be extended through selected register-
ing openings 4 and 7 to secure the sides 3 60
of the section 2 to the bottom plate 6 in spaced
parallel relation and to also secure the section
2 to a pair of base blocks 9. It will be under-
stood that the spacing between the base blocks
9 may be varied within the limits of the series 65
of openings 4—7. The base blocks 9 have
laterally extending end portions provided
with bolt receiving openings 10 whereby bolts
may be projected through said laterally ex-
tending end portions to secure the base blocks 70
9 and the frame section 2 carried thereby
upon a horizontal support such as that indi-
cated at 11 in Figure 2.

It will be apparent from the foregoing that
the frame section 2 will be held against move-
ment when secured to the support 11 in the
manner described. The frame 1 also includes
a movable section indicated at 12 which con-
forms substantially in cross sectional con-
tour to the section 2 and is of less area in 80
cross section than the latter, being supported
by the section 2 to slide in the latter longi-
tudinally thereof from a position in which it
is entirely received within the section 2 to a
position in which the section 12 extends a 85
considerable distance beyond the open end
of the section 2. The sides 3 of the section 2
serve as guides engaging with the correspond-
ing portions of the section 12 for holding the
latter against any appreciable movement 90
laterally of the section 2 without preventing
free sliding movement of the section 12 in the
direction of its length. The section 12 is
closed at its outer end by a transverse plate
13. The ends 13 and 5 of the respective sec-
tions 12 and 2 carry inwardly extending
screw eyes 14 to which a coiled spring 15 is
attached at its opposite ends, the coiled spring
extending through both the section 2 and the
section 12 and urging the section 12 to a 100
position in which it is retracted into the sec-
tion 2.

The sections 2 and 12 may be releasably
held in adjusted position in respect to each
other against the action of the spring 15 by 105
means of a locking pin 16 which is carried at
one end of a lever 17 pivotally supported in-
termediate its length on one of the sides 3 of

the section 2 in position to move the locking pin 16 through an opening in the side 3 into one of a series of openings 18 in the sliding section 12 when the free end portion of the lever 17 is swung outwardly from the outer face of the side 3. A spring 20 urges the free end or handle portion of the lever 17 outwardly and the locking pin 16 thus will be held in engagement with the particular opening 19 which is in register with the opening in the side 3 through which the locking pin extends. The series of openings 19 extends longitudinally of the sliding section 12 and it therefore will be apparent that the combined effective length of the sections 2 and 12 may be varied by placing the locking pin 16 in engagement with the openings 19 selectively.

An upright support 21 is carried by the stationary section 2 at the end of the latter remote from the sliding section 12. The upright support 21 preferably comprises a lower section 22 which is secured to the sides 3 of the section 2 and extends above the plane of the upper side of the section 2 in the form of a pair of parallel vertical arms adapted to straddle the lower end portion of an upper section 23 of the support 21, the lapped portions of the sections 22 and 23 having vertical series of bolt receiving openings formed therethrough, whereby a plurality of bolts 24 may be utilized to secure the upper section 23 rigidly to the lower section 22. This arrangement permits the adjustment of the sections 22 and 23 relatively to each other within a limited range to vary the height of the upright support 21 when the latter is considered as a unit. An upright support 25 which is adapted to cooperate with the upright support 21 in a manner to be hereinafter described is supported by the sliding frame section 12. The upright support 25 includes an upper section 26 which is identical in essential respects with the upper section 23. The upper section 26 is adjustably secured at 27 to a lower section 28 which has a body portion 29 slidably interfitting the section 12. The upright support 25 thus is mounted to slide longitudinally of the section 12 and may be releasably held in any desired position along the latter through the agency of a friction locking lever 30 which comprises a pair of arms 30^a held in spaced parallel relation at their upper ends by means of a cross bar 30^b and having the lower end portions thereof enlarged at 30^c, the edges of the enlarged portions 30^c being rounded and the arms 30^a being pivotally supported by one of the bolts 27 with the axis. With the arrangement described, the enlarged portions 30^c will be swung into frictional engagement with the underlying portions of the section 12 when the lever 30 is grasped at its upper end and swung downwardly about the axis of its pivotal connection with the upright support

25, whereby the upright support 25 will be held against movement relatively to the section 12. When the outer end of the lever 30 has been swung upwardly, the enlarged portions 30^c at the lower ends of the arms 30^a will have been swung out of frictional engagement with the underlying portions of the section 12 and the upright support 25 may be slid longitudinally of the section 12 to any desired position along the latter.

The upright supports 25 and 21 carry at their upper ends pairs of bearings 31 and 32 respectively in the forms of sleeve members secured at 33 to the upper ends of the sections 26 and 23 of the respective upright supports, the bores of the sleeve members 31 and 32 being in axial alignment with each other and each being adapted to receive a rotatable horizontally disposed shaft or spindle 34. The shafts or spindles 34 thus are axially aligned with each other and each extends beyond the opposite end of the bearing sleeve in which it is supported. Lock nuts 35 engage with the spindles 34 at opposite ends of the bearing sleeves to hold the spindles against axial movement relatively to their bearings. A crank handle 36 is secured to the outer end portion of the spindle 34 which is carried by the movable support 25 at the upper end thereof.

The inner end portions of the spindles 34 carry a pair of cooperative work engaging heads 37. Each of the work engaging heads 37 comprises a substantially wedge-shaped and triangular body which tapers both in thickness and in width from the wider end thereof, tapering in thickness to a rounded blunt edge at the narrower end thereof as indicated at 39 in Figure 1 and being provided at its wider and thicker end with a laterally extending continuous flange 40 which is secured in any suitable manner to a transversely extending plate 41. Each work engaging head 37 is attached rigidly to the portion of the spindle 34 which extends thereto through the agency of rivets 42 which extend through the side walls of the body 38, through a spacing and reinforcing sleeve 43 which is mounted on the extending inner end portion of the spindle with the outer end thereof in abutting relation to the plate 41 and which is of sufficient area in cross sectional contour at any point along its length to closely interfit the overlapping portions of the side walls of the body 38, whereby the latter will be held in spaced concentric relation to the extending inner end portions of the spindle and will be stayed to the latter. Each work engaging head 37 is normally held with the major axis thereof vertical by gravity, a weight 44 being secured within the body 38 of the work engaging member at one side of the wider end thereof. The rivets 42 which secure the work engaging members to one of the spindles 34 have the

heads thereof countersunk so that the body of each work engaging head has a smooth outer surface.

From the foregoing description of the various parts of the device, the operation thereof may be readily understood. The frame 1 preferably is secured upon the top of a counter or like support to extend transversely of the latter so that the crank arm 36 will be in a position readily accessible to the operator. The sections 2 and 12 of the supporting frame are of known length and the distance between the work engaging heads 37 therefore may be adjusted initially to accommodate bolts or rolls of fabric up to a certain length by adjusting the position of the sliding section 12 in relation to the stationary section 2. The bolt or roll is then held by the operator in one hand so that the body of the work engaging member carried by the upright support 21 will enter the inner convolution or fold of the bolt or roll at one end of the latter. The bolt or roll then is swung to horizontal position to occupy the position indicated by the dotted lines 45 in Figure 2 and the upright supporting member 25 then is moved toward the other upright support until the body of the second work engaging head has entered the inner convolution or fold of the bolt or roll at the second end of the latter and until the bodies 38 of the two work engaging heads are in such position with respect to each other that the bolt or roll will be held rigid with the heads. The locking lever 30 then is grasped and manipulated to lock the upright support 25 to the section 12. The bolt or roll then will be supported for rotation about the axis common to the spindles 34. In order to unwind or unroll the material from the bolt or roll, it is only necessary that the end of the material be grasped and drawn at right angles to the axis of the bolt or roll until a desired length of material has been taken from the latter. In the event that it is desired to wind the material upon the bolt or roll, the crank handle 36 may be manipulated to effect this result. It will be apparent that the device provides a means whereby varying lengths of material may be taken from or wound upon a bolt or roll expeditiously and without soiling the material, since only the extreme end of the material need be grasped to effect the unwinding or unrolling of the material and the material need not be grasped when it is wound or rolled upon a bolt or roll. Bolts or rolls of various lengths within a wide range may be supported for rotation in the manner described since the distance between the work engaging heads may be varied by adjusting the position of the sliding section 12 in respect to the stationary section 2 and also by varying the position of the upright support 25 along the sliding section 12 or by making only the second named adjustment.

Also, since the bodies of the work engaging heads are substantially wedge-shaped and taper both in thickness and width toward their outer ends, it will be manifest that bolts or rolls in which the inner folds or convolutions have various areas in cross section or various configurations in cross section may be supported by the work engaging heads 37 to rotate therewith.

If desired, the device may be used as a means for winding fabric or like material upon the boards or like supporting cores on which fabric ordinarily is wound or rolled to provide bolts or rolls, since the board or like element may be secured at its ends to the body portions of the work engaging heads 37 in any suitable known manner and the winding of the material thereon effected by turning the crank handle 36.

Obviously, my invention is susceptible of embodiment in forms other than that illustrated in the accompanying drawing and I therefore consider as my own all modifications and adaptations of the form of the device herein disclosed which fairly fall within the scope of the appended claims.

Having thus described the invention, what I claim is:

1. In a device of the character described, an elongated hollow frame section open at one of its ends, means whereby said section may be fixedly secured to a horizontal support so that the longitudinal axis of the section will be horizontally disposed, a second elongated hollow frame section slidably fitting in the first section and adapted to be extended beyond the open end of said first section, an upright supporting member secured to said fixed frame section at the outer end of the latter, a second upright supporting member supported by the slidable section for movement along the latter and being adapted to cooperate with said first supporting member, means whereby said sections may be locked together in adjusted position with respect to each other, means whereby said second upright supporting member may be locked to said slidable section in a desired position on the latter, and a pair of cooperative work engaging heads carried at the upper ends of said upright supporting members.

2. In a device of the character described, an elongated hollow frame section open at one of its ends, means whereby said section may be fixedly secured to a horizontal support so that the longitudinal axis of the section will be horizontally disposed, a second elongated hollow frame section slidably fitting in the first section and adapted to be extended beyond the open end of said first section, an upright supporting member secured to said fixed frame section at the outer end of the latter, a second upright supporting member supported by the slidable section for

movement along the latter and being adapted to cooperate with said first supporting member, means whereby said sections may be locked together in adjusted position with respect to each other, means whereby said second upright supporting member may be locked to said slideable section in a desired position on the latter, a pair of cooperative

work engaging heads carried at the upper ends of said upright supporting members, and spring means connecting said frame sections together and urging said slideable section toward a position in which it is retracted in said fixed section. 10

WOOTTON WALTON JEFFRESS.
